UNITED STATES PATENT OFFICE.

GEORGE L. NORRIS, OF PITTSBURGH, PENNSYLVANIA, ASSIGNOR TO TINIUS OLSEN
TESTING MACHINE COMPANY, OF PHILADELPHIA, PENNSYLVANIA, A CORPOR-
ATION OF PENNSYLVANIA.

ABRASION-TESTING MACHINE.

1,156,803.

Specification of Letters Patent.

Patented Oct. 12, 1915.

Application filed October 2, 1913. Serial No. 792,977.

To all whom it may concern:

Be it known that I, GEORGE L. NORRIS, a citizen of the United States, residing in Pittsburgh, Allegheny county, Pennsylvania, have invented certain Improvements in Abrasion-Testing Machines, of which the following is a specification.

One object of my invention is to provide a relatively simple, substantial and conveniently operated machine for testing the resistance of any material in the shape of a suitable piece, to abrasion, it being further desired that the machine shall include means for applying any suitable load to the piece under test, as well as means whereby the amount of this load may be conveniently observed.

I further desire to provide a machine having the above noted characteristics which shall be particularly adapted to operate upon test pieces of relatively small size and by which it shall be possible to determine the resistance of the given piece to abrasion when subject to any desired loading.

These objects and other advantageous ends I secure as hereinafter set forth, reference being had to the accompanying drawings, in which:—

Figure 1 is a side elevation of a machine constructed according to my invention; Fig. 2 is a front elevation of the machine shown in Fig. 1; Fig. 3 is a fragmentary vertical section on the line *a—a*; Fig. 1; and Fig. 4 is a perspective view of one of the test pieces upon which my machine is designed to operate.

In the above drawings, 1 represents a suitable supporting base structure forming part of or, in the present case, bolted to a hollow column-like frame structure 2 having hinged to one side of its upper end a load applying beam 3, there being provided a pivot bolt 4 whereby this beam is so connected to the frame 2 as to be free to swing in a substantially vertical plane. In the upper part of the frame 2 are provided bearings for two substantially horizontal shafts 5 and 6 which project beyond one side of said frame and have keyed or otherwise fixed to them, two gear wheels 7 and 8 of the same or different diameters as desired. Meshing with both of these gears is a third gear 9 fixed to one end of a driving shaft 10 which on its opposite end is provided with a driving pulley

10^a actuated from any suitable source of power.

Keyed or otherwise suitably fixed to each of the shafts 5 and 6, between the side members of the frame 2, are two rollers 11 and 12, each preferably provided with a central annular groove 13. If the gears 7 and 8 are of different sizes, the rollers 11 and 12 may be both of the same diameter or of different diameters, or if the two gears 1 and 8 are of the same diameter, these rollers are of different diameters so that in any case, the revolution of the driving pulley causes these rollers to turn with differential surface speeds. The load-applying beam 3 is provided with bearings for a third roller 14 likewise having a central annular groove 15 in substantially the same plane as the grooves 13 of the rollers 11 and 12. The free end of this beam 3 is connected through suitable shackles 16 and 17 as well as through the actuating member of a suitable form of tension indicating device 18, with a screw 19 passing through the threaded hub of a hand wheel 20. This latter is mounted between two brackets 21 and 22 forming part of or attached to the frame parts 2 and 1 so that revolution of said wheel will cause longitudinal movement of the screw.

The material whose resistance to abrasion is to be determined is given the form of a relatively small, slightly elongated cylinder *x* (Fig. 4), and is made with a narrow annular rib *x'* of substantially the width of the grooves 13 and 15 of the rollers 11, 12 and 14. Such a test piece is mounted upon the two first of these rollers with its rib *x'* in their grooves 13, after which the load applying beam 3 is given the position shown in Fig. 1 with its roller 14 engaging the test piece whose rib likewise extends into the groove 15. At the same time the main cylindrical surface of said test piece rests in contact with the cylindrical surfaces of the three rollers, and the roller 14 is caused to press upon the test piece with any desired force by manipulation of the hand wheel 20. Said wheel, through the screw 19, the shackles 16 and 17 and the actuating member of the indicating instrument, draws down the free end of the load applying beam, in order to accomplish this end, and the amount of load applied is directly indicated by the pointer 23 of said instrument.

The pulley 10^a is then driven from any suitable source of power and through the shaft 10 and gear 9 consequently drives the gears 7 and 8 together with the rollers 11 and 12. As above noted, the test piece π' is rotated although there is a certain amount of slip between it and one of the rollers which have different surface speeds. The same result is obtained if the gears 7 and 8 are of 10 the same diameters and the rollers are of different diameters. In any case the slip of one of these rollers relatively to the surface of the test piece with which it is engaged causes a greater or less abrasion or 15 wear of the material thereof, and obviously the amount of this abrasion is dependent upon the speed of the rollers 7 and 8 and the load applied through the roller 14 by means of the beam 3 and its associated mechanism, being also dependent upon the time 20 of operation of the machine as well as upon the material of the piece under test.

After the elapse of a predetermined interval, the test piece π may be removed and 25 its loss in diameter determined by suitable measurement or if desired, the amount of abrasion may be determined by weighing before and after it has been subjected to the action of the machine. The three rollers 30 employed may be of any desired or suitable material and more or less roughened and the two driving rollers may be operated at any suitable speed. It is of course to be understood that the test piece may be held from 35 movement parallel to the axes of the shafts 5 and 6 by other means than the rib π' and the complementary grooves in the three rollers, so that in any case, the amount of abrasion occurring under predetermined conditions 40 will be dependent upon the physical qualities of the test piece, when the speed of the rolls, the condition of the roll surfaces and the load applied are constant.

I claim:—

45 1. The combination in an abrasion testing machine of means including two members having differential surface speeds and independently operated to both abrade a test piece; and means for causing said 50 abrading means to operate under a predetermined load.

2. The combination in an abrasion testing machine of means for rotatably supporting a test piece including a rotary 55 abrading member having a cylindrical surface engaging the test piece in position to rotate the same; and means for applying a predetermined load to said test piece; with means for causing slip between said member 60 and the test piece.

3. The combination in an abrasion testing machine of a supporting frame; two rolls mounted to both engage a test piece; means for causing said rolls to have differential surface speeds with means for press-

ing such piece into engagement with said rolls.

4. The combination in an abrasion testing machine of a supporting structure; a plurality of rolls carried thereby and mounted 70 to engage a test piece; means for driving two of said rolls so that they have different surface speeds; and means for positively forcing said rolls and the test piece together.

5. The combination in an abrasion testing 75 machine of a plurality of driven rolls mounted to support a test piece; means for causing one of said rolls to have a certain speed different from the other; a load-applying beam; a third roll carried by said beam in position to engage the test piece; and means for forcing said beam with its roll toward the test piece.

6. The combination in an abrasion testing 85 machine of a plurality of driven rolls each having an annular recess for the reception of the annular rib of a cylindrical testing piece; means for causing one of said rolls to be driven at a surface speed different from that of the other; and means for 90 pressing a test piece toward the rolls with a predetermined force.

7. The combination in an abrasion testing machine of a supporting structure; two rolls carried thereby; means for driving 95 said rolls so that they have different surface speeds; a load-applying beam hinged to the supporting structure; a roll carried by said beam for engagement with the test piece; and means for applying a predetermined 100 load to the free end of said beam.

8. The combination in an abrasion testing machine of a supporting structure; supporting rolls carried thereby; means for driving said rolls so that they have different surface speeds; a load applying beam hinged to the supporting structure; a rotary member carried by said beam for engaging a test piece supported by the two rolls; a hand wheel having a threaded nut; and a 110 screw passing through said nut and connected to the load applying beam.

9. The combination in an abrasion testing machine of a supporting structure; supporting rolls carried thereby; means for driving 115 said rolls so that they have different surface speeds; a load applying beam hinged to the supporting structure; a rotary member carried by said beam for engaging a test piece supported by the two rolls; a hand wheel having a threaded nut; a screw 120 passing through said nut and connected to the load applying beam; and a load indicating instrument interposed between said screw and the beam.

10. The combination in an abrasion testing machine of a plurality of positively driven rolls mounted to act on a test piece; and means for forcing said piece toward said rolls with a definite pressure; the parts 130

of said machine being arranged to cause slip between one of the rolls and the test piece.

11. The combination in an abrasion testing machine of a plurality of positively driven rolls mounted to act on a test piece; means for forcing said piece toward said rolls with a definite pressure; with means for varying at will the force acting to press the test piece toward the rolls, the parts of the machine being arranged to cause slip between one of the rolls and the test piece.

12. The combination in an abrasion testing machine of a plurality of positively

driven rolls mounted to act on a test piece; 15 means for forcing said piece toward said rolls with a definite pressure; with means for preventing relative lateral movement between the rolls and the test piece, the parts of the machine being arranged to cause slip 20 between one of the rolls and the test piece.

In testimony whereof, I have signed my name to this specification, in the presence of two subscribing witnesses.

GEORGE L. NORRIS.
